UNITED STATES PATENT OFFICE.

MARTIN RUSSELL SMITH, OF CHARLOTTESVILLE, VIRGINIA.

VALVE.

1,249,225.

Specification of Letters Patent.

Patented Dec. 4, 1917.

Application filed June 26, 1917. Serial No. 177,104.

To all whom it may concern:

Be it known that I, MARTIN R. SMITH, a citizen of the United States, residing at Charlottesville, in the county of Albemarle and State of Virginia, have invented new and useful Improvements in Valves, of which the following is a specification.

This invention relates to a valve which is especially adapted for use in connection 10 with the flush tanks of closets, and the like.

The primary object of the invention is to provide a valve of this character which will comprise comparatively few parts and may be used in connection with both the old and 15 new style of flush tanks now in use and is so constructed as to insure the seating of the valve upon the completion of the discharge of the water from the tank and to positively prevent the water escaping from the tank 20 into the flush pipe when the valve is seated.

Another object of the invention is to provide a vitreous valve having associated therewith a stem of novel construction which is passed through guides so arranged 25 with relation to the stem as to positively prevent the valve from becoming broken under the influence of the inrush of water to the tank.

A further object of the invention is to 30 provide a seat for a valve of this character which may be mounted upon an outlet pipe forming a part of the valve so as to prevent the seat from becoming distorted and weakened through continuous use.

With these and other objects in view, the 35 invention resides in the novel combination and arrangement of parts, which will be hereinafter described and particularly pointed out in the claims.

The preferred embodiment of the invention 40 has been illustrated in the accompanying drawings, although no restriction is necessarily made to the precise details of construction therein shown, as changes, alterations, and modifications, within the scope of 45 the claims may be resorted to when desired.

In the drawings:

Figure 1 is a longitudinal section through a portion of a flush tank showing the improved valve applied thereto and in elevation.

Fig. 2 is a view similar to Fig. 1, the valve being shown in section.

Fig. 3 is a detailed view through the valve 55 to more clearly illustrate the construction of

the valve stem and manner of connecting the valve therewith.

Like characters of reference denote corresponding parts throughout the several views in the drawings.

Referring now to the drawings in detail, the letter A designates a portion of a flush tank of the type now in common use which has connected therewith the improved valve B. The valve B includes an annular body 5 at the ends of which are formed flanges 6 and 7, the flange 7 being adapted to contact with the bottom of the tank A adjacent the overflow opening therein in which is received a threaded extension 9 on the body 70 for connection with the flush pipe on the closet bowl (not shown in the drawings), said extension being retained in the opening in the tank by a nut 10 between which and the bottom of the tank may be interposed a 75 packing ring 10' if found desirable.

The body 5 has formed thereon a horizontally extending and hollow arm 11 with the outer end of which is connected a vertically extending overflow pipe 12 which serves as a 80 support for a collar 13 which is held in adjusted position thereon by a set screw 14, said collar having formed thereon an extension 15 in which is adjustably mounted a stem 16 having formed integral therewith 85 at its outer end a channeled head 17 for a purpose which will hereinafter appear.

The extension 9 on the body 5 has extending transversely thereof a cross bar 18 in which is formed a vertically extending opening 19 in alinement with the channel in the head 17. A circular valve seat 20 preferably formed from rubber and corresponding in diameter to the diameter of the flange 6 is secured thereto by a ring 21 overlying said 95 seat and flange and having passed therethrough and through openings in the valve seat and flange securing elements 22, such as screws, or the like, which enable the valve seat to be quickly and easily replaced when 100 the occasion requires or permit the reversal thereof if found desirable. The valve seat 20 has formed therein a central circular opening 23, the wall of which is beveled to incline downwardly and outwardly toward 105 the inner surface of the body 5.

I am well aware of the fact that valve seats having a circular opening provided with a beveled wall as shown are in common use but these valve seats are all connected with 110

the valve casings with the beveled wall inclining upwardly and outwardly which permits the valve seat when softened by the water in the tank to allow the water within the tank to pass between the beveled wall of the seat and the valve resting thereon and I find that I can obviate this objectionable feature of these valves by arranging the valve with the beveled wall inclining downwardly and outwardly and clamping the valve on the flange 6 with the ring as shown.

10 A hollow oblate valve 24 to rest upon the seat 20 is preferably formed of some suitable vitreous material and is provided at one of its ends with a reduced and central extension 25 and at its other end with a central opening 26 adjacent which is an opening 27 to allow moisture which may condense within the valve to escape therefrom into the extension 9.

15 A stem for the valve 24 which prevents the valve from being carried against the overflow pipe by the inrush of water and also insures the proper seating of the valve upon its seat 20 includes an interiorly threaded tube 28 which extends longitudinally of the valve 24 and through the opening 26 in one end thereof so that the tube may pass through the opening 19 in the cross bar 18 which serves as a guide therefor. The tube 28 is exteriorly threaded for a portion of its length as at 29 and has engaged with said threaded portion nuts 30 by means of which the extension at the other end of the valve may be firmly engaged with a packing 31 within a cap 32 carried by the other end of the tube and adapted to encircle the extension on the valve. Threadedly retained in the tube 28 is a rod 33 forming the other part of the valve stem and passing through the channel in the head 17 which serves as a guide therefor, the rod being formed above the head with an arm 34 to be engaged by a suitable operating lever (not shown).

20 I am well aware that there are valves somewhat similar to mine now in use which

are suspended by a stem having connection with the overflow pipe but in these valves the stem does not consist of a two-part member which is passed through guides above and below the valve for the purpose set forth but in these valves the stem permits the inrush of water, or the discharge of such water from the tank to cause the valves to swing which prevents the proper seating of the valve and also permits the valve to be struck against guides with which some of the seats are secured in place and broken.

25 From the foregoing description, taken in connection with the accompanying drawing, it is at once apparent that a valve for flush tanks has been provided which will comprise few parts, thus reducing the cost of manufacture and with the parts so connected and arranged as to insure the proper seating of the valve and to positively prevent the escape of water from the tank when the valve is seated.

30 Having thus described the invention, what is claimed as new, is:

1. In a device of the class described, a valve seat and a valve to seat thereon including a hollow oblate body having an extension at one end thereof and an opening at 75 its other end, a tube passing through said body and extending beyond the same through the said opening in the end thereof, a cap at one end of said tube to encircle said extension and close the open end thereof, means 80 on the tube for holding said extension in engagement with said cap, and a rod adjustably mounted in said tube.

2. In a device of the class described, a valve and a seat therefor including an annular body having a flange at one end thereof, a valve seat removably mounted on said flange and having a central circular opening therein, the wall of which inclines downwardly and outwardly toward the inner peripheral wall of the body.

35 In testimony whereof I affix my signature.

MARTIN RUSSELL SMITH.
